UNITED STATES PATENT OFFICE.

SIDNEY REYNELL SMITH, OF LONDON, ENGLAND, ASSIGNOR TO AUTOMATIC TELEPHONE MANUFACTURING COMPANY LIMITED, OF LIVERPOOL, ENGLAND.

VIBRATORY RELAY.

Application filed October 18, 1920. Serial No. 417,839.

To all whom it may concern:

Be it known that SIDNEY REYNELL SMITH, a subject of the King of Great Britain, residing at 14 Leigham Vale, Streatham, London, S. W. 16, England, has invented certain new and useful Improvement in Vibratory Relays (for which I have in part filed an application in England, January 17, 1919, Patent No. 138,966), of which the following is a specification.

The present invention has for its object an arrangement for indicating or utilizing minute vibratory movements of a size incapable of giving either a visual indication or of operating an electrical contact.

Such vibratory movements are, for instance, obtained on a telephone receiver and are at the most not greater than .001", and usually considerably less.

According to the present invention this object is effected by connecting the member, which is subject to vibratory movement of the nature referred to, directly to a movable member so as to exert a greater frictional force along the surface thereof when moving in one direction than when moving in the other, so that the movable member is thereby given a movement in one direction only.

Such a connection preferably consists of a fine thread of wire catgut silk or the like wound partially around the surface of a pivoted cylindrical member and connected at its other end to a spring.

By connecting to the movable member a suitable contact making device a relay is obtained, while by a suitable arrangement the movable member may be arranged to give a visual indication.

It has been found that without any magnification whatever of the vibration the drum will rotate at a speed sufficient to give the required visual indication or to effect the opening or closing of an electrical circuit, and it is believed that this construction is the first to make use of such minute vibrations for this purpose.

Another feature of the present invention is an indicator or relay operated by vibratory movements of the type described and adapted to remain operated until reset.

Another feature of the present invention is a translating device operated by vibratory movements of the type described and adapted to respond sufficiently rapidly to the pres-

ence or absence of movement, so that, for instance signals of high frequency current in Morse code may be converted into ordinary direct current signals capable of operating a sounder in the usual way.

Yet a fourth feature of the present invention is a relay adapted to be operated in response to the vibratory movements and to be deenergized when the vibratory movements cease, so that, for instance, the ringing of a bell may be directly under the control of the calling party.

By way of example, a description will be given of modifications of the parent invention adapted to perform the above functions although it will be understood that modifications can be readily made in the constructional details by those versed in the art without departing from the spirit of the invention.

Referring to the accompanying drawings, Figure 1 illustrates a sectional elevation on the line 1-1 of Figure 2, of an indicator or circuit closing device adapted to respond to vibratory currents and requiring to be manually reset, while Figure 2 shows a plan view. Figure 3 shows an arrangement in which the features of operating a bell or operating the sounder are incorporated in a single instrument while Figure 4 shows an elevation of the device which responds to the vibrations. Fig. 5 is an enlarged view of part of Fig. 1, while Fig. 6 is a cross-section on the line 6-6 of Fig. 5 and shows the method of supporting the armature, this method not being new and forming no part of the present invention; it is briefly described herein merely in order that the operation of the vibrator may be understood.

Referring now to Figures 1 and 2, it will be seen that one end of the reed 1 is secured to a thread 5 of catgut or the like which passes round a cylindrical drum 6 pivoted at 7 and 8 and secured by means of the milled head rod 10. The other end of the reed 1 is limited in its motion by springs 11 and 12 adapted to be adjusted respectively by the screws 13 and 14, so as to avoid the reed contacting with the pole pieces. The reed 1 forms the armature of an electro magnet and is supported inside the former 100 as shown in Fig. 6 by means of the wire 101 so as to operate between the pole pieces 2 and 3 of the permanent magnet 4. There is an elongated slot, as shown at 102 in

Figs. 5 and 6, on the upper side of the former, which enables the wire 101 to be threaded through the holes shown in the lower side of the former and the armature 5 when the armature is held in position shown inside the former, the ends being bent along the former as sharply as possible. The wire is then soldered as shown at 103 and 104 both to the armature and to the former 10 when the temporary supports may be removed, and it will be found that the armature is then supported solely by the wire 101 in a neutral position between the pole pieces 2 and 3, to which neutral position it always 15 tends to return on deflection due to strains being set up in the wire, as will be appreciated.

Pivoted at the rear of the device and extending forwardly are the arms 15 and 16, 20 carrying an indicator plate 17. A rod 18 is pivoted between these arms and carries a member 19 normally resting on the surface of the cylindrical drum 6. A spring 20 secured to the arm 15 and engaging with a 25 hook 21 on the rod 18 holds this rod so that the arm 22 carried at the other end of the rod 18 is forced into engagement with a stop 23 carried by the arm 16. In front of the indicator is the face plate 25 having 30 an opening 26 through which is normally seen the plate 27 which would preferably be of the same colour as the face plate 25 so as to be indistinctive. The operation is as follows:—When a vibratory current such as a 35 buzzer current is passed through the windings of the exciting coil 4, the reed 5 is caused to vibrate in the well known manner, due to its varying polarity and thereby causes the cord 5 to vibrate similarly. It 40 is found that with a suitable adjustment of the spring 9 the pivoted cylindrical member 6 will rotate, due it is believed, to the cord 5 exerting a greater frictional force along the surface of the member 6 when 45 moving away from the member, than when moving towards it. The member 6 therefore rotates in a clockwise direction and thereby causes the member 19 which is pressing against it due to the weight of the 50 arms 15 and 16 and the plate 17, to rotate also. After a short movement, the cylindrical member 6 no longer supports the member 19, whereupon the plate 17 falls in front of the plate 27, this plate 17 being of 55 a distinctive colour serves to give a visual indication. In addition, in a simple bushing in the base plate 28, slides a contact rod 29 which is depressed by the bar 18 when falling, to cause the contact spring 30 to 60 engage with the contact spring 31 mounted on the plate 28 so that a circuit of a bell or other device could be closed, the indicator would then remain in the operated position until manually restored. This is effected in the following manner:—At the

rear end of the arm 15 is fitted a lever 32 having a face plate 33 adapted to be engaged by a rod 34. This rod is controlled by a spring 35 so that it normally remains in the position shown, but when a push button 36, mounted in front of the face plate 25 is pushed, the rod 34 is moved to the left. Now when the indicator is in the operated position, the face plate 33 would be in contact with the end of the rod 34, consequently by pressing the button 36, the arm 32 and with it the indicator 17 is turned in an anti-clockwise direction about the pivots 37 and 38. The spring 20, as soon as the indicator is lifted far enough above the cylindrical member 6, causes the rod 18 to rotate clockwise until the lever 22 engages with the stop 23. In this position, if the push is released the member 19 will be in a position on the surface of the cylindrical member 6 where it can support the arms 17 which therefore remains in the normal position until fresh vibratory currents are received.

It will be appreciated that in this manner, an indicator operated by vibratory currents has been evolved which will give an indication or cause the closure of an electric circuit for an indefinite period, adapted to be terminated by means independent of the vibratory currents received. Such an indicator could conveniently be used in connection with field telephone sets in which buzzer calling was used.

Referring to Figures 3 and 4, the reed 39 is operated similarly to that described with reference to Figures 1 and 2, and is connected by means of a cord 40 round a cylindrical drum 41 to a spring 42 adapted to be adjusted by means of the milled head rod 43, the movable cylindrical member is pivoted on the screws 44 and 45 and carries rings 46 and 47 on its surface preferably of platinum. Against these rings two light flexible metallic springs 48 and 49, provided with platinum contacts are adapted to press lightly; the particular pressure being adjustable by means of the screws 50 and 51. It is found that with a certain adjustment of the screws 50 and 51, the electrical contact resistance between the contact 48 and the ring 46 or the contact 49 and the ring 47 while being practically zero under ordinary conditions, is considerable when the cylindrical member 41 is rotated.

In addition, the cylindrical member carries a wheel 52 provided with projections 53 adapted to force the spring 54 outwards and release it so that it is free to vibrate. Adjacent the spring 54 but normally out of contact with it, is a spring 55 which is adjusted by means of a screw 56 so that the contact member 54 is adapted to make connection with it when set in vibration due to being released by means of one of the

projections 53 when the cylindrical member 41 is rotated.

The instrument shown in Figure 4, is shown in plan view in Figure 3, where in addition is also shown a slow acting relay 57 of the type in which a copper slug 58 is provided adjacent to the armature 59, so that the relay is slow to release, such relays are well known and need not be described.

10 There is also provided on the same base 60, a switching device 61.

These instruments are conveniently located under a cover secured by a bayonet socket joint to the ring 62 in which, the 15 cover being removed, the pins of the bayonet joint are visible at 63 and 64. Outside the cover on the base 60, are fitted 8 terminals, 65, 66, 67, 68, 69, 70, 71 and 72, to which may be connected devices as 20 shown. To the terminals 69 and 70 are connected the lines L' and L² over which high frequency buzzer currents are to be received. These terminals 69 and 70 are permanently connected to the exciting 25 elliptical coil 73 which operates the reed 39. Normally the switching device 61 is in the position shown in the drawings, so that if buzzer currents are received, the reed 39 is caused to vibrate, which thereby 30 causes the movable cylinder 41 to rotate. This causes the projections 53 to maintain the spring 54 in a continual state of vibration, consequently a circuit is intermittently closed as follows:—positive pole 35 of battery 67, winding of slow acting relay 57, terminal 74, contact spring 55, contact spring 54, terminal 75, left hand contact of switching device 76, arm of 40 switching device to terminal 77 and thence to contact 68 and negative pole of battery. The slow acting relay is accordingly 45 energized in this circuit and attracts its armature 59 which remains in the energized position as long as the contacts 54 and 55 are intermittently engaged, that is to say, substantially although not absolutely, in 50 accordance with the vibrations received. When the armature 59 is attracted, the circuit is closed through its contact 78 with the adjustable contact 79 as follows:— 55 positive pole of battery, terminal 65, terminal 80, armature 59, contact 78, contact 79, terminal 81, terminal 66, bell 82 to negative pole of battery. The bell therefore rings in substantial agreement with the vibrations received, so that the attention of the operator may be called by the simple transmission of buzzer currents controlled at will by the calling party. The attendant 60 would then operate the switching device 61, so that the terminal 63 was engaged in place of the terminal 78, then a circuit is closed as follows:—positive pole of battery terminal 67, terminal 71, sounder 84, 65 terminal 72, terminal 85, flexible spring 48,

ring 46 through the movable member 41 to the ring 47, thence via the flexible conductor 49 to the terminal 50, terminal 83, via the switching arm in right hand position to terminal 77, thence to terminal 68 70 and negative pole of battery, the sounder therefore operates. Now if signals are received in the Morse code, the member 41 will be rotated to correspond to the duration of the impulses received and the 75 resistance between the members 46 and 48 and 47 and 49 will be increased for corresponding periods. Consequently the sounder will deenergize for the same periods. In this way, the message transmitted in code 80 using buzzer currents may be adapted to operate a sounder in the usual way. As soon as the message has been received, the switching device would be replaced in its original position in readiness for another 85 call. Obviously, either the contact resistance device or the vibrating contact could be used independently in conjunction with the movable member 41, although as described, there are advantages in combining 90 the two devices.

It will also be appreciated, that by these means it is possible to effect the operation of a sounder by signals received having a high frequency, the sounder 84 operating in strict accordance with the duration of the signals transmitted over the lines L' and L², also, it is possible to make a call, where it is not essential that the devices operated, such as the bell, may be other than under 95 the approximate control of the calling party.

I claim:—

1. Means for responding to vibrations in direct accordance with their duration, comprising in combination, a vibratory member, a movable member having a metallic surface, a flexible metallic member touching said metallic surface and a connection between said vibratory member and said movable member whereby said movable member is given a movement relative to said flexible member thereby increasing the contact resistance between them.

2. Means for responding to vibrations in direct accordance with their duration, comprising in combination, a vibratory member, a movable member having a platinum surface, a flexible metallic member having a platinum contact touching said platinum surface and a connection between said vibratory member and said movable member whereby said movable member is given a movement relative to said flexible member thereby increasing the contact resistance between them.

3. Means for responding to vibrations in direct accordance with their duration, comprising in combination, a vibratory member, a movable member having a metallic

surface, a flexible metallic member touching said metallic surface, and a thread under tension connected to said vibratory member and pressing against said movable member whereby said vibratory member is adapted to exert a greater frictional force along the surface of the movable member when moving in one direction than when moving in the other, so that said movable member is given a movement relative to said flexible member thereby increasing the contact resistance between them.

4. Means for responding to vibrations in direct accordance with their duration, comprising in combination, a vibratory member, a movable member having a platinum surface, a flexible metallic member having a platinum contact touching said platinum surface and a thread under tension connected to said vibratory member and pressing against said movable member whereby said movable member is given a movement relative to said flexible member thereby increasing the contact resistance between them.

5. Means for responding to vibrations in direct accordance with their duration, comprising in combination, a vibratory member, a movable member having a metallic surface, a flexible metallic member touching said metallic surface, a circuit including a source of electrical energy and a detector in series with said flexible metallic member and said metallic surface, and a connection between said vibratory member and said movable member whereby said movable member is given a movement relative to said flexible member thereby increasing the contact resistance between them, so that the detector responds to the vibrations.

6. Means for responding to vibrations in direct accordance with their duration, comprising in combination, a vibratory member, a movable member having a metallic surface, a flexible metallic member touching said metallic surface, a circuit including a source of direct current and a detector in series with said flexible metallic member and said metallic surface, and a connection between said vibratory member and said movable member whereby said movable member is given a movement relative to said flexible member thereby increasing the contact resistance between them, so that the detector responds to the vibrations.

7. Means for responding to vibrations in direct accordance with their duration, comprising in combination, a vibratory member, a pivotal cylindrical member having a metallic surface, a flexible metallic member touching said metallic surface and a connection between said vibratory member and said pivotal cylindrical member whereby said cylindrical member is caused to rotate thereby increasing the contact resistance between the metallic members.

8. Means for responding to vibrations in direct accordance with their duration, comprising in combination, a vibratory member, a pivotal cylindrical member having a metallic surface, a flexible metallic member touching said metallic surface and a thread under tension connected to said vibratory member pressing against the surface of said pivoted cylindrical member whereby said cylindrical member is caused to rotate thereby increasing the contact resistance between the metallic members.

9. Means for responding to vibrations in direct accordance with their duration, comprising in combination, a vibratory member, a pivoted cylindrical member having a metallic surface, a flexible metallic member touching said metallic surface, a circuit including a source of electrical energy and a detector in series with said flexible metallic member and said metallic surface, and a connection between said vibratory member and said pivoted cylindrical member whereby said cylindrical member is given a movement relative to said flexible member thereby increasing the contact resistance between them, so that the detector responds to the vibrations.

10. Means for responding to vibrations in direct accordance with their duration, comprising in combination, a vibratory member, a pivoted cylindrical member having a metallic surface, a flexible metallic member touching said metallic surface, a circuit including a source of electrical energy and a sounder in series with said flexible metallic member and said metallic surface, and a connection between said vibratory member and said cylindrical member whereby said cylindrical member is given a movement relative to said flexible member thereby increasing the contact resistance between them, so that the sounder responds to the vibrations.

11. Means for responding to vibrations in direct accordance with their duration, comprising in combination, a vibratory member, an electrical member for causing said vibratory member to operate, a pivoted cylindrical member having a metallic surface, a flexible metallic member touching said metallic surface, a circuit including a source of electrical energy and a detector in series with said flexible metallic member and said metallic surface, and a connection between said vibratory member and said cylindrical member whereby said cylindrical member is given a movement relative to said flexible member thereby increasing the contact resistance between them, so that the detector responds to the vibrations.

12. Means for responding to vibrations in direct accordance with their duration, comprising in combination, a reed, an electromagnet for causing said reed to vibrate, a movable member having a metallic sur-

face, a flexible metallic member touching said metallic surface and a connection between said reed and said movable member whereby said movable member is given a 5 movement relative to said flexible member thereby increasing the contact resistance between them.

13. Means for responding to vibrations in approximate accordance with their duration, 10 comprising in combination, a vibratory member, a rotatable member, a circuit closing device actuated by said rotatable member when rotating, a slow acting relay controlled by said circuit closing device, a connection 15 between said vibratory member and said rotatable member whereby said rotatable member is given sufficient movement to effect the actuation of said circuit closing device and the operation of the slow acting 20 relay in response to the vibrations of the vibratory member.

14. Means for responding to vibrations in approximate accordance with their duration, comprising in combination, a vibratory member, a rotatable member, contact 25 springs actuated by said rotatable member when rotating, a slow acting relay adapted to be excited when said contact springs are operated, a connection between said vibratory member and said rotatable member whereby said rotatable member is given sufficient movement to effect the actuation of the contact springs and the operation of the slow acting relay in response to the vibrations 30 of the vibratory member.

15. Means for responding to vibrations in approximate accordance with their duration, comprising in combination, a vibratory member, a movable member, a contact 40 spring adapted to be set in vibration by said movable member, a second contact spring normally separated from said first mentioned contact springs but adapted to be engaged by it when set in vibration, a relay of the slow to release type adapted to be excited when said second contact spring 45 is engaged by said first contact spring and to remain excited during said vibrations, a connection between said vibratory member 50 and said movable member whereby the movable member is given sufficient movement to effect the actuation of said first mentioned contact spring, and the operation of the slow acting relay in response to the vibrations 55 of the vibratory member.

16. Means for responding to vibrations in approximate accordance with their duration, comprising in combination, a vibratory member, a movable member, projections on 60 said movable member, a contact spring adapted to be set in vibration by the projections on said movable member, a second contact spring normally separated from said first mentioned contact spring but adapted 65 to be engaged by it when set in vibration,

a relay of the slow to release type adapted to be excited when said second contact spring is engaged by said first contact spring and to remain excited during said vibrations, a connection between said vibratory 70 member and said movable member whereby said movable member is given sufficient movement to effect the actuation of said first mentioned contact spring, and the operation of the slow acting relay in response to the 75 vibrations of the vibratory member.

17. In combination, a movable member, projections on said movable member, a contact spring adapted to be set in vibration by said projections, a second contact spring 80 normally separated from said first mentioned contact spring but adapted to be engaged by it when set in vibration and a relay of the slow to release type adapted to be excited when said relay is set in vibration and to remain excited during said vibration.

18. Means for responding to vibrations in approximate accordance with their duration, comprising in combination, a vibratory 90 member, a movable member, a circuit closing device actuated by said movable member, a slow acting relay controlled by said circuit closing device, a thread under tension connected to said vibratory member 95 and pressing against said movable member whereby said movable member is given sufficient movement to effect the actuation of said circuit closing device and the operation of the slow acting relay in response to the 100 vibrations of the vibratory member.

19. Means for responding to vibrations in approximate accordance with their duration, comprising in combination, a vibratory member, a movable member, a circuit closing device actuated by said movable member, a slow acting relay controlled by said circuit closing device, a signalling device controlled by said slow acting relay, a thread 105 under tension connected to said vibratory member and pressing against said movable member, whereby the movable member is given sufficient movement to effect the actuation of said circuit closing device and the operation of the signalling device in approximate 110 accordance with the vibrations of the vibratory member.

20. An electric relay device comprising in combination an electromagnetic device responsive to intermittent vibratory currents, 115 a circuit, means controlled by said device for causing variations of current in said circuit exactly corresponding in duration with the variations of current received by said device, a second circuit, a second means controlled by said device for causing variations of current in said second circuit which differ considerably in duration from the variations of current received by said device and switching means adapted to 120 125 130

- close one or other of said circuits without interrupting the response of said electromagnetic device.
21. An electric relay device comprising in combination a vibratory member, an electromagnet for causing said vibratory member to vibrate, a movable member, connection between said vibratory member and said movable member whereby said movable member is given a continuous movement, a circuit controlled by said movable member so as to have a variations of current corresponding exactly to the movements of said movable member so as to have variations of current corresponding approximately to the movement of said movable member, and switching means adapted to close one or other of said circuits without interrupting the response of said vibratory member.
22. An electrical relay device comprising in combination, a vibratory member, an electromagnet for causing said vibratory member to vibrate, a movable member a connection between said vibratory member and said movable member whereby said movable member is given a continuous movement, a metallic surface on said movable member, a flexible metallic conductor touching said surface in such a manner that the electrical contact resistance increases when in relative motion, a circuit closing device controlled by said movable member, a slow acting relay controlled by said circuit closing device and switching means for connecting either the variable contact or the circuit closing device into circuit without interrupting the response of said vibratory member.
23. An electrical relay device comprising in combination, a vibratory member, an electromagnet for causing said vibratory member to vibrate, a movable member a connection between said vibratory member and said movable member, whereby said movable member is given a continuous movement, a metallic surface on said movable member, a flexible metallic conductor touching said surface in such a manner that the electrical contact resistance increases when in relative motion, a circuit closing device controlled by said movable member, a slow acting relay controlled by said circuit closing device, a detector controlled by the contact resistance between said metallic surface and said metallic conductor, a second detector controlled by said slow acting relay and switching means for bringing either the first or second detector into action without interrupting the response of said vibratory member.
24. An electrical relay device comprising in combination a vibratory member, an electromagnet for causing said vibratory member to vibrate, a movable member, a connection between said vibratory member and said movable member whereby said movable member is given a continuous movement, a metallic surface on said movable member, a flexible metallic conductor touching said surface in such a manner that the electrical contact resistance increases when in relative motion, a circuit closing device controlled by said movable member, a slow acting relay controlled by said circuit closing device, a sounder controlled by the contact resistance between said metallic surface and said metallic conductor, a bell controlled by said slow acting relay and switching means for bringing either the bell or the sounder into circuit according as to whether it is desired that the instrument should respond to a call or to code messages energizing said electromagnet, without interrupting the response of said vibratory member.
25. Means for detecting or utilizing minute vibrations, comprising in combination, a vibratory member, a movable member, a contact making and breaking device associated with said movable member and a connection between said vibratory member and said movable member, whereby said movable member is adapted to exert a greater frictional force along the surface of the movable member when moving in one direction than when moving in the other, so that the response of the vibratory member to minute vibrations, causes said movable member to move in one direction only sufficient to effect the operation of said contact making device.
26. Means for detecting or utilizing minute vibrations comprising in combination, a vibratory member, subject to minute vibrations, a movable member, an indicating device associated with said movable member, and a connection between said vibratory member and said movable member whereby said movable member is adapted to exert a greater frictional force along the surface of the movable member when moving in one direction than when moving in the other, so that the response of the vibratory member to minute vibrations causes said movable member to move in one direction only sufficient to effect the operation of said indicating device.
27. Means for detecting or utilizing minute vibrations, comprising in combination, a vibratory member, a movable member, a contact making and breaking device associated with said movable member and a thread under tension connected to said vibratory member and pressing against the surface of said movable member, whereby said movable member is adapted to exert a greater frictional force along the surface of the movable member when moving in one direction than when moving in the other so that the response of the vibratory member to minute vibrations, causes said movable

member to move in one direction only sufficient to effect the operation of said contact making device.

28. Means for detecting or utilizing minute vibrations comprising in combination, a vibratory member subject to minute vibrations, a movable member, an indicating device associated with said movable member and a thread under tension connected to said vibratory member and pressing against the surface of said movable member whereby said movable member is adapted to exert a greater frictional force along the surface of

the movable member when moving in one direction than when moving in the other, so 15 that the response of the vibratory member to minute vibrations causes said movable member to move in one direction only sufficient to effect the operation of said indicating device. 20

In testimony whereof I affix my signature in presence of two witnesses.
